(57) **CLAIM**

The ornamental design for a dessicant assembly as shown and described.

DESCRIPTION

FIG. 1 is a front perspective view of a first variant of the article, said first variant of the article being provided with a given number of folding sections;

FIG. 2 is a rear perspective view thereof;

FIG. 3 is a top view thereof;

FIG. 4 is a bottom view thereof;

FIG. 5 is a front plan view thereof;

FIG. 6 is a rear plan view thereof;

FIG. 7 is a left side elevational view thereof;

FIG. 8 is a right side elevational view thereof;

FIG. 9 is another front perspective view of what is shown in FIG. 1, the article being now shown provided with top and bottom containment components corresponding to environment components of the article;

FIG. 10 is a front perspective view of a second variant of the article;

FIG. 11 is a rear perspective view thereof;

FIG. 12 is a top view thereof;

FIG. 13 is a bottom view thereof;

FIG. 14 is a front plan view thereof;

FIG. 15 is a rear plan view thereof;

FIG. 16 is a left side elevational view thereof;

FIG. 17 is a right side elevational view thereof; and,

FIG. 18 is another front perspective view of what is shown in FIG. 10, the article being now shown provided with top and bottom containment components corresponding to environment components of the article.

The broken lines shown in the figures are for the purpose of illustrating portions of the article and environment and form no part of the claimed design.

The article is shown with a symbolic break in its length in FIGS. 10-18. The appearance of any portion of the article between the break lines forms no part of the claimed design.

1 Claim, 18 Drawing Sheets
